Patented Sept. 13, 1927.

UNITED STATES PATENT OFFICE.

CHARLES R. LION, OF LOS ANGELES, CALIFORNIA.

AUTOMATIC SEWER FLUSHER.

Application filed June 20, 1927. Serial No. 200,035.

My invention is an automatic sewer flusher of the type for automatically flushing sanitary sewers by discharging periodically a quantity of flushing water into the sewer. 5 My invention may be considered as an improvement on the automatic sewer flusher of Garrie H. Burns #1,256,656, issued February 19, 1918, and is illustrated embodied with my copending applications for 10 an automatic sewer flusher, Serial Nos. 200,034 and 200,036 filed June 20, 1927.

In automatic sewer flushers difficulty has been found to maintain the proper adjustment of the balancing pan which is filled 15 with water and when filled lifts the valve bell. It is necessary that initially the pan be adjusted by an adjustable screw threaded arrangement to receive the proper amount of water in order to become loaded 20 with the proper weight before dropping and actuating the valve. After the threads become rusted the adjustment becomes displaced, therefore dropping the balancing pan either so that it allows the overflow water 25 to run away or else does not sufficiently raise or actuate the valve bell.

An object of my invention is the construction of a screw threaded connector device pivotally mounted on a lever or walking beam of a flusher so that when the adjustment is once made it will not become altered.

My invention will be more readily understood from the following description 35 and drawings, in which:

Figure 1 is a section through the manhole and well of a sewer flushing system, showing the installation of my automatic flusher.

Figure 2 is a side elevation of the connection of the pan operated rod with the lever or walking beam.

Figure 3 is a vertical section of Fig. 2 on the line 3—3.

In the drawings the manhole structure is 45 designated generally by the numeral 1 in which usually vertical walls 2 are formed above a well 3, the well having walls 4 on a suitable base 5, there being a sewer pipe 6 discharging into the well and another sewer 50 pipe 7 discharging out of the well. This construction is sometimes arranged so that the walls 4 are connected directly to the sewers, if these are of large size, and the well flushes directly into an opening formed

in the sewer pipe. A structural frame 8, 55 usually formed of an angle iron having a T-shaped section, is embedded in the walls of the manhole, and the floor 9 for the flushing device is suitably mounted on this angular frame. A tubular flushing column 10 60 extends upwardly from the floor and has a pan operated rod 11 extending therethrough, the pan 12 being in the well and pivotally hung from a bracket 13 or the like depending from the floor. 65

In the usual construction an upper arm 14 extends laterally from the tubular flushing column and has the lever or walking beam 15 pivoted at the other end of same. A valve rod 16 depends from this lever, being 70 guided in the outer end of a guide arm 17, the valve bell 18 being hung on the lower end of the valve rod and seating in the valve seat 19, which has a large opening to allow quick flushing. 75

The connection between the walking beam 15 and the pan operated rod 11 is substantially as follows, having reference particularly to Figures 2 and 3:

The pan operating lever is formed with a vertical opening 20 therethrough with a slot at the end, and with notches 21 on the side to form a journal. A cross trunnion 22 is journaled in said notches. The upper part of the trunnion has a cylindrical surface 23 on which is mounted a threaded cylindrical pin 23'. A swivel rod 24 has its lower end enlarged, forming a nut end 25 in which is threaded the upper end 26 of the operating rod 11. The trunnion 22 has a central enlarged recess 27 and a clear opening 28 at the top to allow passage of the swivel rod 24. This construction of the trunnion 22 and the cylindrical pin 23' allows a universal joint type of action. 85 90 95

It will be seen by this construction that the pan operating rod 11 and the swivel rod 24 are maintained in substantial alignment by the screw-threaded connection, but on account of the rod 24 being threaded on the pin 23', this has a swiveling action in regard to the walking beam 15 and on the action of this beam. When it is desired to adjust the relative length of the pan operating rod, the pan can be elevated so that the pin 22 is disengaged from the notches 21 and this revolved in one direction or the other to thread it up or down on the swivel 100 105

rod 24; or if desired, this rod 24 may be threaded to a greater or lesser extent on the end 26 of the pan operating rod 11.

Water is continuously discharged into the manhole through the inlet pipe 30, having a control valve 31, which will be set to allow the desired flow. When the bell valve is seated, outlet from the manhole is prevented and the same is filled with water until it overflows the top of the flushing column, flowing down into the dumping pan 12. When this pan receives a sufficient weight of water it tilts downwardly discharging the water into the well, this action pulling downwardly on the pan rod 11, which motion is transmitted through the swivel rod 24 and the trunnion to one end of the lever 15; thus lifting the valve rod 16 and the valve bell 18, allowing the water in the manhole to be discharged into the well, thus flushing the sewer, or directly into the sewer where the manhole is connected directly on the sewer structure.

While I have illustrated my connecting device from the pan rod to the lever as being used with a particular type of automatic sewer flusher, it is to be understood that a similar or other connection may be used for other types of flushers.

Various changes may be made in the principles of my invention without departing from the spirit thereof, as set forth in the description, drawings and claims.

I claim:

1. In an automatic sewer flusher having a flushing column, a pan, a pan rod extending through the column connected to said pan, a lever operatively connected to a valve bell, and an adjustable swiveling connection between the pan rod and the lever.
2. In an automatic sewer flusher having a flushing column, a pan rod connected to a pan extending therethrough, a lever operatively connected to a valve bell, a swivel rod, means journaling said rod on the lever, and a connection between the swivel rod and the pan rod.
3. In an automatic sewer flusher having a flushing column with a pan rod connected to a pan extending therethrough, a lever operatively connected to a valve bell, a rocking trunnion mounted on the lever, a swivel

rod extending through said trunnion and connected to the pan rod, and means to support the swivel rod on the trunnion.

55

4. In an automatic sewer flusher having a flushing column with a pan rod connected to a pan extending therethrough, a lever operatively connected to a valve bell, a trunnion mounted on the lever, a swivel rod extending loosely through the trunnion and being connected to the pan rod, the trunnion having a curved upper surface, and a threaded pin having a lower bearing surface on the curved surface of the trunnion, said threaded pin being connected to the swivel rod.

60

5. In an automatic sewer flusher having a flushing column with a pan rod connected to a pan extending therethrough, a lever operatively connected to the flushing column and operating a valve bell, the lever having a vertical opening therethrough at one end and a pair of transverse notches, a trunnion having its opposite ends journaled in said notches, said trunnion having an opening therethrough from top to bottom, a swivel rod extending through said opening and having a connection with the pan rod, and a threaded oscillating pin mounted on the trunnion, the axis of said pin being at right angles to the axis of the trunnion, and said pin engaging the said swivel rod.

70

6. In an automatic sewer flusher having a flushing column with a pan rod connected to a pan extending therethrough, a lever operatively connected to the flushing column and having a valve bell connected thereto, the lever having a vertical opening therethrough and transverse notches on opposite sides of the opening, a trunnion having rounded ends fitting in said notches, a trunnion having a central opening from top to bottom, a swivel rod extending through said opening and connected to the pan rod, a pin having threads transversely therethrough connected to the swivel rod, said pin having a lower cylindrical surface bearing on the cylindrical surface of the trunnion at right angles to the axis of the trunnion.

90

95

In testimony whereof I have signed my name to this specification.

CHARLES R. LION.
